UNITED STATES PATENT OFFICE.

WALTER C. CARLSON, OF MILWAUKEE, WISCONSIN, ASSIGNOR TO MILWAUKEE PAPER
BOX COMPANY, OF MILWAUKEE, WISCONSIN, A CORPORATION OF WISCONSIN.

DESIGN FOR A BOX FOR FACE-POWDER.

48,363.

Specification for Design.

Patented Jan. 4, 1916.

Application filed October 21, 1915. Serial No. 57,199. Term of patent 3½ years.

To all whom it may concern:

Be it known that I, WALTER C. CARLSON, a citizen of the United States, residing at Milwaukee, in the county of Milwaukee and State of Wisconsin, have invented a new, original, and ornamental Design for a Box for Face-Powder, of which the following is a specification, reference being had to the accompanying drawing, forming part thereof, and in which—for face powder, showing my new design. Fig. 2 is a plan view of the same. Fig. 3 is a side elevation.

I claim—

The ornamental design for a box for face powder, as shown.

WALTER C. CARLSON.
